Edgar V. Johnson

UNITED STATES PATENT OFFICE.

WILLIAM H. JOHNSON, OF ARLINGTON, NEW JERSEY.

GARTER.

1,386,935.

Specification of Letters Patent. Patented Aug. 9, 1921.

Application filed September 1, 1920. Serial No. 407,430.

To all whom it may concern:

Be it known that I, WILLIAM H. JOHNSON, a citizen of the United States, and residing at Arlington, in the county of Hudson and State of New Jersey, have invented certain new and useful Improvements in Garters, of which the following is a specification, such as will enable those skilled in the art to which it appertains to make and use the same.

This invention relates to garters and particularly to devices of this class worn by men; and the object thereof is to provide a garter of this class which will snugly fit the leg below the knee, or at the top of the calf portion of the leg without crimping or folding when in use, and which will not bind or pinch the leg or slip downwardly thereon; and with this and other objects in view the invention consists in a device of the class specified, constructed as herein-after described and claimed.

The invention is fully disclosed in the following specification, of which the accompanying drawing forms a part, in which the separate parts of my improvement are designated by suitable reference characters in each of the views, and in which:—

Figure 1 is a view of a part of a leg and showing one of my improved garters and the method of its use;

Fig. 2 a plan view of a garter detached and extended; and,

Fig. 3 a view similar to Fig. 2 but showing a modification and showing parts broken away.

In the practice of my invention, as shown in Figs. 1 and 2, I provide a garter *a* comprising a main strap member *b*—*c* divided into two main end parts or portions *d* and *e* which are connected at *f*.

The part *d* is composed of any suitable fabric, preferably two sheets stitched together, and preferably non-elastic, while the part *c* is preferably composed of elastic material in the usual manner but which may be composed of non-elastic material, if desired.

The part *d* of my improved garter is curved upwardly in the plane of the main strap *b*—*c* as clearly shown in Figs. 1 and 2, and this curvature renders said part *d* arc-shaped in form and causes it when the garter is in use to snugly fit that portion of the calf of the leg just below the knee, as indicated at *x* in Fig. 1.

This form of the part *d* of the garter is what constitutes the principal feature of my invention, and what causes the garter to operate in the manner hereinbefore set out, 60 or to closely fit the leg and to rest snugly on the top or curved portion of the calf of the leg at the back thereof, and this also prevents the garter from twisting or folding when in use, the connection of the two ends 65 of the garter around the leg, as shown at *x*, causing said garter to snugly fit the leg at all times, and causing the pull on the hanger strap *g* to be equally and evenly distributed over the entire garter. 70

The free end portion of the part *d* of the garter is provided with the usual male member *h* of the usual spring attaching clip device, the female member *i* of which is connected with the free end portion of the part 75 *e* of the garter, and whereby the garter is secured around the leg, and the part *e* of the garter is formed at its free end into a loop *j* in the usual manner by means of a buckle *k*, which is adjustably mounted on 80 the body portion of the part *e*.

The hanger strap *g* is provided with the usual spring clip attaching members *m* and *n* whereby the garter is connected with the top portion of a sock as indicated at *o* in 85 Fig. 1, and while I have described my improved garter as particularly designed for use by men, it will be apparent that my invention is not limited to this or any other particular use of a device of this class, and 90 my improved garter or garters may be used by women, children or anybody who desires to use them.

It will be observed that the construction shown in Fig. 3 differs mainly from that shown in Figs. 1 and 2 only by reason of the fact that there are two suspending sock attaching hanger straps *g* employed, one at each end of the curved portion *d* of the garter and with this construction when the garter is in use there will be sock attaching hanger straps at both sides of the leg. 95

From the foregoing description it will be seen that in the construction or formation of my improved garter as shown and described, I dispense entirely with what is known as the usual front pad employed in devices of this class, and with which the usual leg encircling strap is connected, and in lieu thereof I provide only a main strap member 100 adapted to encircle the leg below the knee and that part which is designed to encircle the 105 110

back part of the leg when in use being curved upwardly in the plane of the strap member, or formed on the arc of a circle in order to cause said part of the garter when in use to 5 closely fit that part of the leg below the knee at the back of the leg and thus prevent the garter from slipping down, or crimping, or twisting in any way when in use, and it will be apparent that the extent or degree of the 10 curvature of said part of the garter may be varied or made greater, if desired, than that shown in the drawing, the essential element in this connection being that said curvature be sufficient to cause said part of the garter 15 when in use to closely fit the back of the leg below the knee for the purposes, and to accomplish the result hereinbefore set out, but in this connection it is necessary to state that my invention is not necessarily limited 20 to the exclusion of a front pad member as it will be evident that a front pad member may be employed, if desired, in which event that part of the strap which encircles the back part of the leg below the knee would be 25 formed on an upwardly directed curve or on the arc of a circle as hereinbefore set out.

Having fully described my invention, what I claim as new and desire to secure by Letters Patent, is:—

30 1. In a garter, a main strap member consisting of two connected parts, one of which is composed of elastic material and the other of which is upwardly curved in the plane of the strap member, said strap member being 35 also provided with means whereby it may be

secured around the leg and with means whereby it may be secured to a stocking.

2. In a garter, an expandible and contractible strap member adapted to encircle a leg below the knee and provided with means for connecting it with a sock or stocking, the said strap member being curved upwardly along both its upper and lower edges at a portion of its length, the remaining portion being straight. 40

45 3. In a garter, an expandible and contractible strap member adpted to encircle a leg below the knee and provided with means for connecting it with a stocking, said strap member being curved upwardly along both its upper and lower edges at that portion of its length adapted to engage the back of the leg below the knee and the remaining portion being straight. 50

4. In a garter, a leg encircling strap member having means for detachably connecting its ends together and means for connecting it with the top portion of a sock or stocking, said strap member being curved upwardly at that portion of its length which engages 60 the back of the leg below the knee and the remaining portion being straight. 55

In testimony that I claim the foregoing as my invention I have signed my name in presence of the subscribing witnesses this 65 30th day of August, 1920.

WILLIAM H. JOHNSON.
